UNITED STATES PATENT OFFICE.

EDWARD DAVID ANSON, OF WILLAMETTE, OREGON.

DESIGN FOR A FLOWER-VASE HOLDER.

Application filed September 14, 1928. Serial No. 28,142. Term of patent 7 years.

To all whom it may concern:

Be it known that I, EDWARD DAVID ANSON, a citizen of the United States of America, and a resident of Willamette, in the county of Clackamas and State of Oregon, have invented a new, original, and ornamental Design for a Flower-Vase Holder, of which the following is a specification, reference being had to the accompanying drawing, forming part thereof.

I claim:

The ornamental design for a flower vase holder, as shown.

EDWARD DAVID ANSON.
